United States Patent

Des. 239,197

Patented Mar. 16, 1976

239,197

LAMP

James T. Poston, 8109 Clover Way,
Buena Park, Calif. 90620

Filed July 29, 1974, Ser. No. 492,415

Term of patent 3½ years

Int. Cl. D26—05

U.S. Cl. D48—20 R

FIG. 1

FIG. 2

FIG. 3

FIG. 4

FIG. 5

FIG. 1 is a perspective view of a lamp showing my new design looking downwardly;

FIG. 2 is a perspective view of the lamp looking upwardly;

FIG. 3 is an elevational view thereof, the glass being shown in broken lines for illustrative purposes only;

FIG. 4 is an enlarged top plan view, the wick assembly being omitted for convenience of illustration; and

FIG. 5 is an enlarged bottom plan view thereof.

I claim:

The ornamental design for a lamp, substantially as shown and described.
